Walter H. Henning and Eugenia Williams
Henning, Los Angeles, Calif.

Application September 3, 1953, Serial No. 26,693

Term of patent 7 years

(Cl. D85—2)

To all whom it may concern:

Be it known that we, Walter H. Henning and Eugenia Williams Henning, both citizens of the United States, residing at Los Angeles, in the county of Los Angeles and State of California, respectively, have invented a new, original, and ornamental Design for an Ash Tray, of which the following is a specification, reference being had to the accompanying drawing, forming part thereof.

Fig. 1 is a perspective view of an ash tray, showing our new design;

Fig. 2 is a side elevational view thereof;

Fig. 3 is an end elevational view thereof; and

Fig. 4 is a fragmentary cross-sectional view thereof, taken on line 4—4 in Fig. 3.

We claim:

The ornamental design for an ash tray, as shown.

WALTER H. HENNING.
EUGENIA WILLIAMS HENNING.
